UNITED STATES PATENT OFFICE.

HENRY L. COAKLEY, OF NEW YORK, N. Y.

AEROPLANE.

1,110,895.

Specification of Letters Patent. Patented Sept. 15, 1914.

Application filed April 7, 1914. Serial No. 830,313.

To all whom it may concern:

Be it known that I, HENRY L. COAKLEY, a citizen of the United States, and a resident of the city of New York, borough of Manhattan, in the county and State of New York, have invented a new and Improved Aeroplane, of which the following is a full, clear, and exact description.

This invention relates to aerial navigation, and has particular reference to aeroplanes.

Among the objects of the invention is to improve the construction of aeroplanes with reference especially to the controlling devices.

More definitely stated, by this invention I am enabled to control by a single and simple expediency all of the movements of the aeroplane while in the air. The controlling devices including a plurality of controlling planes are arranged preferably at the rear, said planes being journaled on substantially horizontal axes extending transversely of the line of flight but at an angle to each other.

A further object of the invention is to provide a controlling means for the steering devices which will be of such nature as to respond naturally to all of the movements of the aviator's body in accordance with the desire or necessity at any particular time, as for instance, in ascending or descending or turning to the right or left.

The foregoing and other objects of the invention will hereinafter be more fully set forth and claimed, and illustrated in the drawings forming a part of this specification in which like characters of reference indicate corresponding parts in all the views, and in which—

Figure 1 is a perspective view of a biplane involving the principles of this invention; Fig. 2 is a side view of the same; Fig. 3 is a plan view of a slightly modified form of biplane; Fig. 4 is a perspective view in diagram of the controller connections; Figs. 5 and 6 are front elevations of other modifications of biplanes; and Fig. 7 is a plan view of a monoplane, all of said views being more or less diagrammatic in nature.

The several parts of the device may be made of any suitable materials, and the relative sizes and proportions, as well as the general design of the mechanism, may be varied to a considerable extent without

departing from the spirit of the invention hereinafter more fully described and specifically claimed.

Referring more particularly to the drawings, I show in Figs. 1 and 2 a biplane having upper and lower planes 10 and 11 connected by any suitable braces 12 and guys 13. At the rear end of the machine and supported by diagonal braces 14 are controlling planes 15 and 16 each mounted upon a substantially horizontal axis and movable upwardly or downwardly around the same by any suitable means. As shown herein, the supporting axis for each controlling plane is in the nature of a shaft 17 bent or turned at an angle 17' and hence serving for the axes of both planes. Each controlling plane is provided with a pair of hinges or straps 18 extending around the shaft 17 and each plane, furthermore, is provided with a lever 19 connected at any desired place intermediate its ends and preferably along its front edge, said lever extending at right angles to the plane of the member to which it is connected.

The controlling means under the immediate charge of the aviator includes a transverse shaft 20 journaled at 21 in the rigid framework of the aeroplane, and said shaft is adapted to rotate around said horizontal axis in either direction. A shaft 22 is journaled at 23 in the middle portion of the transverse shaft 20 and extends perpendicularly thereto. This shaft 22 is provided with a hand wheel 24 or the equivalent thereof, whereby the aviator may either rotate the shaft 22 alone or rock the shaft 20 without rotating the shaft 22, or he may combine the two motions, rotating both the shaft 22 and the rock shaft 20.

A pair of wheels or pulleys 25 and 26 are secured rigidly to the shaft 22 above and below the bearing 23 respectively and preferably at equal distances therefrom. These pulleys 25 and 26 are preferably parallel to each other and of the same size. It will be understood that the aviator will be seated on any convenient seat (not shown) just in the rear of the hand wheel 24.

At 27 and 28 I provide a pair of flexible non-elastic connections, such as high grade wire cables or the like, operating respectively over the pulleys 25 and 26. The ends of the cable 27 are connected at 29 to the lower ends of the two levers 19 above described. The ends of the cable 28 are con-

ected at 30 to the upper ends of said levers 19, the intermediate portions of the cable 28, however, being crossed at 28' between the pulley 26 and the points of connection 30.

5 As viewed in Fig. 4, the full lines indicate the normal positions of the several parts. The dotted lines indicate changed positions with the rotation of the shaft 22 as indicated by the arrows above the hand 10 wheel but without rocking the shaft 20. Rotation of the hand wheel, as shown, it being understood that the cables 27 and 28 are always maintained substantially taut, will cause the cable 27 to pull forwardly on the point 29 of the lever connected to the controlling plane 16, and at the same time the cable 28 will draw forwardly upon the point 30 of the lever connected to the plane 15. This will cause the plane 16 to swing down- 15 wardly on its axis and the other plane to swing in the opposite direction. This will cause the machine as a whole to rotate around its longitudinal central axis and thereby tilt downwardly on the right hand 20 side and upwardly on the left hand side. The effect of this action will be to cause the machine to turn to the right without affecting its elevation. So long, therefore, as the hand wheel is turned in the direction indicated, 25 the tendency for the machine will be to circle toward the right. A rotation of the hand wheel in the opposite direction from the normal would have a similar effect upon the machine, guiding it in a circle 30 toward the left. These movements of the hand wheel are, as above intimated, according to the aviator's natural inclination when he wishes to steer in any direction.

If it be desired to ascend, the aviator will 40 tilt his body backwardly, pulling rearwardly upon the hand wheel 24, and without rotating the shaft 22, causing the rock shaft to rotate and causing the cable 28 to pull forwardly on both the points 30, swinging both 45 of the controlling planes 15 and 16 upwardly around their axes. The cable 27 will be relieved in the same proportion as the cable 28 is drawn upon, allowing such movement of the levers 19. Likewise, the descent will be 50 effected by a forward thrust on the hand wheel and draft through the cable 27 upon the points 29, causing the planes 15 and 16 to swing downwardly. Since the rotation of the shaft 22 and that of the rock shaft 20 55 are independent of each other, it is obvious that the two motions or two effects upon the steering mechanism may be combined in a single movement; that is to say, the aviator, for instance, by rotating the hand wheel 60 toward the right and at the same time pulling rearwardly upon it so as to rotate both of the shafts 22 and 20, the machine will be steered both to the right and upwardly.

It will be noted that the axes of the two 65 controlling planes 15 and 16 are arranged

at an angle to each other which may be more or less obtuse according to the design of the builder of the machine. This arrangement of the supporting shaft for the controlling planes and their action therearound make it impossible for the aviator to operate the planes too far in either direction, which has heretofore caused much difficulty when steering planes connected for simultaneous movement have been employed. In other words, 70 the planes 15 and 16 being pivoted on angularly disposed axes are adapted to partake somewhat of the nature of a screw when rotated in opposite directions; that is to say, as shown in dotted lines in Fig. 4, viewed longitudinally or along the central axis of the machine, the effect is that of a right handed spiral or screw. If these planes should be rotated to their maximum extent, 75 they still present the nature of a screw and hence at no time offer a positive obstruction to the movement of the machine through the air. If, however, the planes were to be mounted on a single horizontal axis and each swung through an angle of 90 degrees, 80 there would be an enormous resistance to the machine due to the disposition of the planes perpendicularly to the line of movement of the aeroplane. Such resistance proves disastrous. 85

It is obvious that the number and form of the main planes may be varied to a large extent. In Figs. 1 and 2, I show a pair of planes 10 and 11 which are substantially straight in plan but diverging from each other toward their ends. In Fig. 3 I show a biplane in which the upper planes 10^a has a nose or point at the front and with its ends directed somewhat rearwardly. The plane 11^a is somewhat of the same shape but arranged with its sides or ends projecting forwardly slightly. In Fig. 5 I show a view indicating the appearance of the biplane of Fig. 1 as seen from the front, and in Fig. 6 I show a similar view of a machine in which 100 the lower plane 11^b is substantially straight throughout. 105

As above premised, the amount of angularity of the shaft 17 may vary greatly in different constructions, depending upon the 115 size of the machine and the shape of the main planes. In Fig. 7, for instance, I show a monoplane, the supporting plane 10^b of which has its ends inclined toward the rear, and straight lines *a* and *b* drawn through 120 the centers of the ends of the main plane intersect each other between the main plane and the controlling planes 15 and 16 and also intersect the controlling planes on opposite sides of the machine. Corresponding 125 lines *a'* and *b'* drawn on Fig. 3 perpendicularly to the centers of the front edges of the controlling planes intersect each other comparatively close to the main planes and consequently do not pass through the centers 130

of the ends of said main planes. The operation of the rock shaft 20, the steering shaft 22, the wheel 24 and cables 27 and 28 is substantially the same in all the forms of 5 the invention illustrated.

In the preferred form of the invention shown in Figs. 1, 2 and 5, each of the machine planes 10 and 11 is of peculiar form and they both have a peculiar relation to 10 each other. That is to say, each plane comprises two wings extending laterally from the longitudinal center of the machine and said wings at their outer portions are arranged at an obtuse angle to each other. 15 More specifically, the ends or wings of the main plane 10 extend upwardly and the ends or wings of the lower main plane 11 extend downwardly. It will be noted, furthermore, that the angles formed by these 20 upwardly and downwardly extending wings are substantially equal, and, hence, either of the upwardly projecting wings of the upper plane lies in a plane substantially parallel to the downwardly projecting wing 25 of the lower plane on the other side of the machine. The effect of this peculiar construction is important and may be appreciated by reference especially to Fig. 1. A great source of trouble and accident in aero- 30 plane practice lies in the tendency for the machine to guide, skid or oscillate laterally. Especially is the oscillation a common source of annoyance and danger. By this term is meant the tendency for the aero- 35 plane to swing to and fro laterally around the imaginary center above the machine in the nature of a clock pendulum. When this trouble takes place, especially when the machine is falling, there is an extreme ten- 40 dency for the oscillation to increase in amplitude and speed due to the combined oscillating and gravitating motions; hence, the machine is most certain under ordinary conditions to turn upside-down at the end of 45 one of the oscillating movements. In my improvement, however, the tendency to lateral movement, either as a gliding or an oscillating motion, is resisted effectively by the coöperation of the two wings of the 50 upper and lower planes which, lying on opposite sides of the longitudinal axis of the machine, present the maximum surface to the air. In other words, when the machine is being operated, and on a tilt, such as may 55 be presumed to be shown by Fig. 1, with the left hand wing of the upper plane presenting considerable resistance surface and the opposite wing of the same plane more nearly horizontal, the wing of the lower plane on 60 the right hand side of the machine extending downwardly presents substantially as much surface to the air in proportion to its length as does the wing first mentioned, and, furthermore, the left hand wing of the lower 65 plane is substantially horizontal. It is true,

as stated hereinbefore, however, that the lower main plane is shorter preferably than the upper plane, but nevertheless the wings are of sufficient length to provide the resistance desired to prevent the oscillating of 70 the machine.

Having thus described my invention, I claim as new and desire to secure by Letters Patent, I claim:

1. The herein described biplane comprising upper and lower main supporting planes, the upper plane being longer than the lower plane, each plane comprising a pair of laterally extending wings arranged at an angle to each other, the wings of the upper plane 75 projecting upwardly, the wings of the lower plane projecting downwardly, and each wing on one side of the machine lying in a plane substantially parallel to the wing on the other plane on the opposite side of the 80 machine, a main supporting frame, a pair of controlling planes adjacent each other and journaled upon the main supporting frame at the rear of the main planes, and means to manipulate the controlling planes 85 so as to produce either a right or left hand spiral effect upon the entire machine with respect to its longitudinal axis.

2. In an aeroplane, the combination of a frame, a rigid main supporting plane secured thereto, a pair of controlling planes in the rear of the main supporting plane journaled upon the frame on axes at an angle to each other, a horizontal rock shaft journaled in the main frame, a shaft journaled in the rock shaft perpendicular thereto, a hand device to rotate either the shaft or the rock shaft or both at the same time, and cables extending from the perpendicular shaft to the controlling planes whereby 95 the controlling planes are made responsive to the rotations of the two shafts aforesaid.

3. In a controlling device for aeroplanes, the combination of a horizontal rock shaft, a rotary shaft journaled in the rock shaft and 100 perpendicular thereto, a pair of pulleys connected to the rotary shaft on opposite sides of the rock shaft and in parallel planes, a pair of controlling planes remote from the rock shaft and pivoted on axes at an angle 105 to each other and lying in substantially the same plane as the rock shaft, a lever arranged perpendicularly with respect to each controlling plane extending to both sides thereof, and a pair of cables operating over 110 said pulleys, the ends of one cable being connected to the lower ends of said controlling plane levers and the ends of the other cable being connected to the upper ends of 115 said levers.

4. In a controlling device for aeroplanes, the combination of a rock shaft journaled on a fixed horizontal axis transversely of the machine, a rotary shaft journaled in the rock shaft and perpendicularly thereto, a 120

hand wheel secured to the upper end of the rotary shaft, a pair of pulleys of equal size arranged parallel to each other at equal distances on opposite sides of the rock shaft 5 and secured to the rotary shaft, a pair of controlling planes mounted on horizontal axes in the rear of the rock shaft, a lever secured to each plane perpendicularly thereto and extending above and below its axis, a 10 cable extending around one of said pulleys and having its ends connected to the lower ends of the controlling plane levers, and

another cable extending around the other pulley and having its ends crossed and connected to the upper ends of said levers, substantially as set forth. 15

In testimony whereof I have signed my name to this specification in the presence of two subscribing witnesses.

HENRY L. COAKLEY.
